FORREST E. FINK, OF BUCYRUS, OHIO.

PROCESS OF PRODUCING GAS.

1,031,781.

Specification of Letters Patent.

Patented July 9, 1912.

Application filed July 10, 1911. Serial No. 637,590.

To all whom it may concern:

Be it known that I, FORREST E. FINK, citizen of the United States, residing at Bucyrus, in the county of Crawford and State 5 of Ohio, have invented certain new and useful Improvements in Processes of Producing Gas, of which the following is a specification.

My invention relates to an improved process of producing gas from coal or other fuels, and particularly bituminous coal, using a gas producer of my own invention, and the object of my improved process is to produce in the most efficient and economical manner, a fixed clean gas, free from tar, lampblack and other impurities, by steps involving a single charging of the producer with a deep bed of coal sufficient to last several days or a week, and in maintaining a downwardly shifting zone of incandescent fire in the bed of coal until all the coal is consumed and without feeding or replenishing the supply of coal throughout the entire run after the first or extreme 25 top zone of incandescent fire is established.

Obviously, my process advantageously maintains an unvarying condition of fire, and consequently causes a continuous and uniform generation of gas of unvarying 30 composition, and the quality of the gas is of a high and uniform standard from start to finish of gas-producing operations. Continuous or intermittent charging of the producer being eliminated during a single long run, the cost of the gas is brought low due to the minimum amount of labor required to operate the producer, and for the further reason that a saving of coal is also effected, that is, there is not the waste of coal incident to charging operations of other processes known to me to produce the heat of combustion of the coal in converting it into gas, as no further feeding or charging of coal is practised by me after the first zone of fire has been established.

In the accompanying drawing, the single figure represents a sectional view of an improved gas producer of my own invention which is particularly adapted to carry out 50 my process in a highly efficient manner and with the best results, but it must be understood that any other simple and efficient apparatus may be used, providing the construction and arrangement of parts permits 55 the working of the process. As shown,

however, the producer comprises a casing 2 of any suitable form having the requisite dimensions to hold a bed of coal of sufficient depth for the continuous production of gas for several days (or a week or more) without replenishment of coal during that entire period. Casing 2 is lined internally with fire brick 3 or other suitable material and the upper end of the fire-lining is preferably of conical form although this may be otherwise arranged. A cover 4 incloses the top of the producer. A feed hopper 5 is shown supported centrally on cover 4. The producer may be filled with coal from an overhead bin 6 having a slide valve 7 at its bottom directly above hopper 5, or the cover 4 may be bodily removed for filling purposes.

Feeding of the coal may be accomplished by other means than as described, but in any event it is not intended that feeding of coal shall proceed through hopper 5 at intermittent intervals after the bed of coal has once been properly fired, but only at the start of operations, and therefore, the hopper 5 and its bell-shaped valve 8 may be placed out of commission or entirely removed after a zone of fire has been established at the extreme top of the bed of coal. Cover plate 4 is also provided with suitable openings 9 for poking the fire, and similar poke openings 10 are provided at different elevations in the side wall of the producer. A circular grate 11 is also shown as arranged within the bottom of the producer apart from casing 2, and air and steam or air alone may be introduced into the bed of coal uniformly at all radial points from the annular chamber 12 surrounding grate 11, the steam or air being admitted into chamber 12 at one or more points through suitable pipe connections 14 located at the outside of the producer. A centrally arranged hood or spreader 15 is also shown as extending into the producer through brick-lined bottom 16 for the distribution of air and steam, or air alone, into the bed of coal, the supply of fluid being obtained from pipes 17 having pressure connections, or the air and steam may be drawn into the producer by suction if the producer is worked on the suction principle.

The bottom 16 has one or more openings 18 provided with slide valves 19 to remove the contents of the producer in small quan-

tities, whether in the form of ashes or other refuse, but in view of the fact that no ashes form at the bottom of the producer until the finish of operations—following my process, no interruption of the production of gas ensues. An ash-receiving hopper 20 having a slide valve 21 may be attached to bottom 16, and an ash-carrying car 22 may be arranged to run beneath the hopper. Bottom 16 may also be pivotally mounted or provided with a hinge 23 to swing downward to permit emptying of the entire contents of the producer in a quick and expeditious manner.

Now having in mind a producer of approximately the kind described, the following steps are taken by me to produce a clean gas of exceptional good composition and heat value. Thus, my first step is to fill the producer nearly full of fuel or with in a few feet of cover-plate 4 and below gas outlet 25, the amount of fuel stored greatly exceeding present practices and being sufficient to last for several days, a week, or even longer. My second step is now contra-distinguished from present practices by starting a fire on top of the deep bed of coal, or in other words, in the extreme upper end of the producer. To accomplish this successfully and to provide a top zone of incandescent fire of several feet in depth, or to a depth sufficient for all purposes of producing a fixed gas, a draft is induced throughout the entire bed of coal, and fresh coal—generally coke—supplied from time to time from hopper 5 until this particular zone of fire is established. At this time the products of combustion are permitted to escape through draft stack 26. After a gas-producing zone of fire is once fully developed—a matter of a few hours—no further coal is supplied to the producer, and the remainder of the run—covering several days or longer—proceeds by the gradual consumption of the coal beneath the zone of fire, the fire working downward into the green fuel as fast as it is consumed, or possibly faster. Poking is also resorted to (but not as often as in other processes) to promote uniform combustion of the fuel and to maintain a uniform depth of the zone of fire as it works downward, and the amount of air and steam passing through the body of green fuel must be regulated to correspond with the gradually decreasing depth of the bed of coal to also maintain a uniform depth of zone of fire. In poking and forcing or passing steam or air through the green fuel, precaution must also be taken to prevent the fire from working downward too fast to avoid the formation of tar and to produce a clean gas of consistent composition and uniform quality. The elimination of coal-charging steps during the production of the gas obviously prevents a variation in the

condition of the fire, and consequently avoids a variation in the composition of the gas generated, and by maintaining an undisturbed zone of fire constantly on top of a bed of green fuel the forcing of steam and air through the same from below entirely breaks up the tar, lampblack and other waste products, such as condensable hydrocarbon vapors, and transforms them into a useful fixed gas free from tar and other impurities and fit to be piped long distances. After the zone of fire has worked down to the bottom of the producer, say at the close of several days operations, the usual final steps are taken to stop gas-producing operations and the ashes and contents of the producer may then be dumped and carted away. Then the producer is cooled off and again charged for another run of long duration, and the above cycle of operations repeated.

My process and apparatus requires less attention and care than other methods and apparatus known to me, there being a great saving of labor and time in eliminating the charging operations as now generally practised and the constant removal and handling of ashes; but doubtless, the greatest advantage lies in the maintenance of an incandescent zone, the upper layer of which always remains undisturbed in an unvarying state of combustion and incandescence to effectively combine the oxygen of the air with the carbon to form carbon dioxid CO_2 , and in passing through to reduce this to carbon monoxid, CO , which escapes with the hydrogen and carbon monoxid and with the nitrogen which came in with the air to produce the resultant fixed gas of exceptional quality and high heat value of my process.

The producer as herein described may be modified in many respects to meet various requirements of different installations or types of plants—a pressure plant, or a suction plant.

In a pressure plant using my process, the air pressure will vary from $2\frac{1}{2}$ inches to perhaps 5 inches, whereas other types usually require five to eight inches;—measuring a five inch pressure as equal to a column of water five inches deep. The average steam pressure required is less than that usually employed in other processes, varying from 15 to 60 pounds dependent upon the kind and quality of fuel used. In the matter of the amount of fuel transformed into gas per square foot of area of the diameter of the producer, I find eight to eleven pounds per square foot of area a desirable rate, or the margin may be 4 to 12 pounds.

The size and diameter of the producer may vary considerably, but the one I have operated successfully is approximately fifteen feet high and twenty-eight inches internal diameter, inside the brick wall. This

size producer I roughly rate as a twenty-five horse power unit. A 600 horse power unit would be approximately twenty-five feet tall and about eleven feet internal diameter. However, the conditions might be such as to prohibit the use of a producer twenty-five feet tall. In such a case the height can be brought down to perhaps eighteen or twenty feet, at the same time increasing the diameter sufficiently to maintain the cubical volume required to retain the required amount of fuel for each run. The two types above mentioned are of ample size to hold sufficient fuel to last approximately seventy or eighty hours, or a week's run. As to the temperature of the incandescent zone, I roughly estimate my producer to operate at a temperature of from 1800° to 2150° F., or about 100° to 125° Fahrenheit higher than in other average types.

What I claim is:

1. A process of producing a fixed gas from bituminous coal or other fuels, consisting in storing a deep bed of fuel in a gas producer and in maintaining a zone of incandescent fire at successively lower elevations throughout the day and from day to day for a fixed period without substantial variation of the condition of the fire, and in passing steam and air through the green bed of fuel from the bottom upward and through said zone of fire.
2. A process of producing a fixed gas of good and uniform quality, consisting in charging a gas producer with a deep bed of fuel, then firing the top layer of said bed of coal with additional fuel until a top zone of incandescent fire is fixedly established, then continuously producing gas by the passing of steam and air under regulation through the bed of coal from the bottom upward and into said zone of fire to gradually work the zone of fire downward over a period of several days without further charging of the fire with fuel and until all the fuel in the producer is consumed.
3. A process of continuously producing a fixed gas of uniform composition, consisting in storing up a bed of fuel sufficient to burn

continuously without replenishment for a period of several days or longer when fired from the top and in igniting said bed of fuel at its top and working a zone of fire downwardly substantially as fast as complete combustion will permit without the formation of tar by introducing air and steam or air alone into the bed of coal from below.

4. A process of producing a fixed gas of uniform quality for a continuous period of several days or longer, consisting in filling a gas producer of deep dimensions with a single charge of fuel reaching substantially to its top and in firing the top strata of fuel and then working a zone of fire gradually downward and without adding fuel or removing the ash until all or substantially all the fuel is consumed, and in introducing air and steam in regulated amounts into the bed of fuel from below to correspond with the gradually decreasing depth of said bed during the operations aforesaid.

5. A process of producing gas, consisting in charging a producer with a bed of green coal, establishing a zone of fire on top of said bed, and maintaining a uniform zone of fire at successively lower elevations by an up-draft of air through the bed of coal, the amount of air being regulated to correspond with the gradually decreasing depth of the said bed.

6. A process of making gas consisting in charging a producer with a bed of fuel and in establishing and maintaining a top zone of fire with an up-draft and without introducing further fuel after the zone of fire becomes incandescent.

7. A process of producing gas consisting in filling a producer of desired dimensions with a charge of fuel and establishing a top zone of fire and maintaining the same at successively lower elevations with an up-draft for a period of several days without recharge of fuel.

In testimony whereof I affix my signature in presence of two witnesses.
